(57) **CLAIM**

The ornamental design for a coil component as shown and described.

DESCRIPTION

FIG. 1 is a right-side elevational view of a first embodiment of a coil component, showing the new design;

FIG. 2 is a left-side elevational view thereof;

FIG. 3 is a front elevational view thereof;

FIG. 4 is a bottom plan view thereof;

FIG. 5 is a rear elevational view thereof; and

FIG. 6 is a top plan view thereof.

FIG. 7 is a right-side elevational view of a second embodiment of a coil component, showing the new design;

FIG. 8 is a left-side elevational view thereof;

FIG. 9 is a front elevational view thereof;

FIG. 10 is a bottom plan view thereof;

FIG. 11 is a rear elevational view thereof; and

FIG. 12 is a top plan view thereof.

FIG. 13 is a right-side elevational view of a third embodiment of a coil component, showing the new design;

FIG. 14 is a left-side elevational view thereof;

FIG. 15 is a front elevational view thereof;

FIG. 16 is a bottom plan view thereof;

FIG. 17 is a rear elevational view thereof; and,

FIG. 18 is a top plan view thereof.

The broken lines depict parts of the coil component that form no part of the claimed design.
